UNITED STATES PATENT OFFICE.

JOHN L. MCATREE, OF NEW YORK, N. Y., ASSIGNOR TO SCOVILL MANUFACTURING COMPANY, OF WATERBURY, CONNECTICUT, A CORPORATION OF CONNECTICUT.

VANITY BOX.

Application filed January 16, 1926. Serial No. 81,650.

This invention relates to certain improvements in vanity boxes or cases.

These vanity cases are small boxes largely used by ladies for carrying cosmetics, such as rouge, powder, lipsticks and the like. It is desirable in this type of box that the case be as small as possible to carry the required cosmetics, and which shall be thin and of attractive appearance. These cases generally include a body and cover that are pivotally associated and, to improve the appearance of the box, it is very desirable that the hinge or pivot by which the parts are united should be invisible, particularly when the box is closed.

The particular object of the present invention is to produce a box of this character which shall be small, relatively thin, and in which the cover and body are so united that the hinge or pivot is entirely concealed when the box is closed.

A further object of the invention is to provide an improved construction for holding the hinge in position in the box after assembly.

A further object of the invention is to produce an improved box which may be thin and which at the same time may be used for two kinds of cosmetics and a lipstick.

With these and other objects not specifically referred to, the invention consists in certain novel parts, arrangements and combinations which will be described in connection with the accompanying drawings and the novel features pointed out in the claims hereunto annexed.

In these drawings,—

Figure 1 is a top view of the improved box closed;

Figure 2 is a side view of the same;

Figure 3 is a face view of the box open;

Figure 4 is a sectional view, partly broken away, the section being taken on line 4—4 of Fig. 3;

Figure 5 is a sectional view of the box shown in its open position, the section being taken on line 5—5 of Fig. 3, and

Figure 6 is a face view of a modified form of box, the box being shown in its open position.

Referring now to these drawings, the particular box shown includes a body 1 and a cover 2. The body is formed with a side wall 3 and this side wall is turned in at the

top to form a continuous peripheral top 55 flange or rim 4, as shown in Fig. 1.

Pivots associated with this body is the cover 2, this cover being provided with a depending flange 6 which snugly fits within the peripheral flange 4 of the body. As shown in Fig. 1, the cover is or may be provided with a finger catch 6' by which the parts may be separated.

It will be seen, referring to Fig. 1, that when the box is closed no part of the hinge or pivot by which the parts are associated shows, a smooth continuous surface being provided entirely around the box. The invention includes a hinge or pivot of im-

proved construction which is so arranged and assembled that it is entirely concealed within the flanges of the body and the cover, so that a box as shown in Fig. 1 may be produced. While this hinge may be of va-

rious characters and formed in various ways, in the particular construction illustrated this hinge is a U-shaped piece of spring wire 7 which fits around three sides of the cover of the box, being dimensioned to snugly fit within the flange. This wire is U-shaped and at the open end of the U the ends of the wire are slightly bent or turned to form short legs 8, 9, which act as the pintle of the hinge. These legs take bearing in

notches 10 in an internal strip 11 which is secured inside the flange 4 of the body 1, this strip extending around the body and forming a seat for the flange 6 of the cover, the flanges having frictional engagement with each other.

The spring wire is held in position and is concealed in any suitable manner. In the particular construction illustrated, the cover is provided with a mirror 12, this mirror being dimensioned to snugly fit in the cover between the legs of the wire hinge so that when this mirror is put in place it acts to

spread the legs of the wire and hold them in the flange 11 of the body. The wire may be concealed and the parts further held in place by means of a bezel 13 which is

snapped into position in the cover, as shown in Fig. 3, this bezel acting to hold the parts together and concealing the wire hinge.

Boxes embodying the invention will include means for holding one or more cosmetics. In the particular construction shown, a two part box is illustrated, having a pow-

der compartment 14 and a small rouge compartment 15. The powder and rouge may be held in these compartments in any suitable manner. As shown, they will be carried by trays 16, 17. These trays are preferably separated by a partition 18 formed of a strip of metal which is held in position by being sprung into notches formed in the flange strip 11, before referred to, and the trays may be removably held in position by cutting out projections 18' from the metal of the flange strip 11, as shown in Fig. 5. It will, of course, be understood that, if desired, a one compartment box may be provided, in which case the compartment 15 may be omitted. In Fig. 6 a two compartment box having means for carrying a lipstick is shown. Where such a box is desired, the powder and rouge do not occupy the whole of the body, but a space 19 is left for the reception of a lipstick which may be carried in a recess 20 formed in the cover, the mirror in this modified form of box not occupying the whole of the cover. With this construction a lipstick can rest partly in the recess 19 and partly in the recess 20 when the box is closed, so that a lipstick can be used with a very thin box.

30 While the box has been shown and described in its preferred form, it will be understood that various changes may be made in the specific structure shown, and the invention, therefore, is not to be limited exactly to the box shown.

What I claim is:

1. In a case of the character described, the combination of a rectangular body having a side wall the upper edges of which are turned in to form a continuous peripheral top flange or rim, a rectangular cover having a depending flange and arranged when closed to fit the space within the rim, and a pivot uniting the parts frictionally held by the rim and flange so as to be invisible when the box is closed.
2. In a case of the character described, the combination of a rectangular body having a side wall the upper edges of which are turned in to form a continuous periph-

eral top flange or rim, a rectangular cover having a depending flange and dimensioned to snugly fit within the rim when closed, a U-shaped pintle for pivotally uniting the parts entirely within the rim and flange, and means for holding the pintle in assembled position.

3. In a case of the character described, the combination of a rectangular body having a continuous inturned peripheral top flange or rim, a cover arranged when closed to fit the space within the rim, a U-shaped spring wire supported in the cover and having legs engaging under the rim of the body for pivotally uniting the body and cover, and means for holding the wire in assembled position.

4. In a case of the character described, the combination of a rectangular body having an inturned flange or rim, a holding strip located within the rim, a cover having a depending flange, a U-shaped spring wire located within the flange of the cover and having legs engaging the holding strip for pivotally uniting the body and cover, and means for springing the legs of the wire into engagement with the holding strip.

5. In a case of the character described, the combination of a body, a cover having a depending flange, a spring wire located in the cover and having legs engaging with the body for pivotally uniting the body and cover, a mirror in the cover dimensioned to cause the engagement of the spring with the cover, and a bezel for holding the mirror in place.

6. In a case of the character described, the combination of a body having an inturned peripheral top flange, a cover having a depending flange, a spring wire located within the flange of the cover and having outwardly turned ends, a holding strip in the body with which the ends of the wire engage for pivotally uniting the body and cover, projections struck out from the holding strip, and a compact carrying member frictionally held by the projections.

In testimony whereof, I have hereunto set my hand.

JOHN L. McATREE.
